182,413

BIRD CAGE

Alan V. Hinton, Brooklyn, N. Y.

Application December 6, 1956, Serial No. 44,095

Term of patent 14 years

(Cl. D31—2)

FIG. 1

Des. 182,413

PAGE 2

FIG. 2

Des. 182,413

PAGE 3

FIG. 3

FIG. 5
FIG. 4

Figure 1 is a front elevational view of a bird cage showing my new design;

Figure 2 is a rear elevation thereof, the windows shown in Figure 1 being omitted for convenience of illustration; Figure 3 is a plan view;

Figure 4 is a side elevation taken from the left of Figure 1; and

Figure 5 is a side elevation taken from the right of Figure 1.

I claim:

The ornamental design for a bird cage, as shown and described.
